United States Patent

Des. 241,862
Patented Oct. 12, 1976

241,862

PEELABLE CHESS GAME CARD

Anthony J. Cioffi, 114 Branchport Ave.,
Long Branch, N.J. 07740

Filed Feb. 25, 1974, Ser. No. 445,124

Term of patent 14 years

Int. Cl. D21—01

U.S. Cl. D34—5 SS

FIG 1

The figure is a plan view of a peelable chess game card showing my new design.

The card is of no appreciable thickness.

I claim:

The ornamental design for a peelable chess game card, substantially as shown and described.

References Cited

UNITED STATES PATENTS

D. 131,043 1/1942 Hopper ----- D34—5 SS
2,585,924 2/1952 Freedman et al. ----- D34—5 SS

MELVIN B. FEIFER, Primary Examiner